UNITED STATES PATENT OFFICE

MARK W. PETERS, OF GLEN RIDGE, NEW JERSEY, ASSIGNOR TO EAGLE PENCIL COMPANY, OF NEW YORK, N. Y., A CORPORATION OF DELAWARE

DESIGN FOR A FOUNTAIN PEN HOLDER

Application filed July 30, 1931. Serial No. 40,735. Term of patent 7 years.

To all whom it may concern:

Be it known that I, MARK W. PETERS, a citizen of the United States, residing at Glen Ridge, in the county of Essex and State of New Jersey, have invented a new, original, and ornamental Design for a Fountain Pen Holder, of which the following is a specification, reference being had to the accompanying drawings, forming part thereof, in which

Figs. 1, 2 and 3 are top, side and bottom views, respectively, of a fountain pen holder showing my new design.

I claim:

The ornamental design for a fountain pen holder, substantially as shown.

MARK W. PETERS.
